HARRY P. SPARKES, OF PITTSBURGH, PENNSYLVANIA.

SURGE-DETECTING RELAY.

Application filed May 24, 1923. Serial No. 641,038.

To all whom it may concern:

Be it known that I, HARRY P. SPARKES, a citizen of the United States, and a resident of Pittsburgh, in the county of Allegheny and State of Pennsylvania, have invented a new and useful Improvement in Surge-Detecting Relays, of which the following is a specification.

My invention relates to relay systems and particularly to systems for detecting surges in an electrical circuit.

One object of my invention is to provide means for distinguishing between surges of current in an electrical system and gradual increase of current.

Another object of my invention is to provide means for detecting an increase of current when the rate of increase thereof exceeds a predetermined rate of change.

A further object of my invention is to employ such means as indicated above for controlling an electrical circuit in which such conditions may occur.

In practicing my invention, I provide a balance relay embodying two elements and energize one element from the circuit and control the energization of the other element of the relay by means of a Kelvin balance device which is also energized from the circuit. As the current in the circuit increases, the corresponding element of the balance relay is energized and, if such increase in the circuit current is gradual, the Kelvin balance will control the energization of the counteracting element to effect a balance between both elements. If the increase in the circuit current is rapid, such as if caused by occurrence of short-circuit conditions, the corresponding element of the relay will be energized quickly and will serve to operate the relay before the Kelvin balance may correspondingly affect the energization of the counteracting element. The faulty portion of the circuit may thereupon be disconnected.

The single figure of the accompanying drawing is a diagrammatic view of an electrical system containing the apparatus embodying my invention.

As illustrated in the drawing, electrical energy is supplied from a source of supply 1 to a circuit 2 through a circuit interrupter 3. The value of the current traversing the circuit 2 is measured by means of a current transformer 4.

In order to distinguish between a normal

increase in the value of the current that traverses the circuit 2 and a surge such as may be caused by short-circuit conditions in the circuit 2, I provide a balance relay 5 and a Kelvin balance 6.

The balance relay 5 comprises an operating element 7 that is energized from the current transformer 4, a counteracting element 8, a plurality of contact members 9 and 10, engagement of which is controlled by a pivoted member 11, and a spring 12 which also serves to control, in cooperation with the elements 7 and 8, the movement of the pivoted member 11.

The Kelvin balance 6 comprises a standard control balance element 15 which is energized from the current transformer 4 in series with the operating element 7 of the balance relay 5. The pivoted operating element of the balance relay controls, by means of a switching device 16, the circuits of the two field windings 17 and 18 of a reversible motor 19. The motor 19 controls a threaded member 20 which, in turn, controls the movement of a sliding contact member 21 in engaging a resistor 22. The resistor 22 is energized from a source of constant potential 23.

Upon referring to the drawing, it will be seen that the counteracting element 8 is so connected to the resistor 22 as to be energized in accordance with the potential difference across the portion of the resistor included between the point 24 and the point of engagement of the sliding contact member 21 with the resistor 22.

As the current in the circuit 2 increases gradually, the operating element 7 of the balance relay 5 increases and tends to effect engagement between the contact members 9 and 10. Simultaneously, however, the switching device 16 of the Kelvin balance effects the energization of the winding 17 of the reversible motor 19 to shift the sliding contact member 21 towards the right-hand side, thereby increasing the potential difference impressed upon the counteracting element 8. The balance relay 5 is thereby maintained in a state of balance and the contact members 9 and 10 are maintained disengaged.

Upon the occurrence of a surge, such as that caused by short-circuit conditions in the circuit 2, the element 7 becomes immediately energized to a great degree, tending thereby to effect engagement of the contact

members 9 and 10. Simultaneously, as in the other condition, the Kelvin balance operates to shift the sliding contact member 21 towards the right-hand side to increase the energization of the counteracting element 8.

Since the increase in the energization of the counteracting element 8 is dependent upon the rate of speed at which the sliding contact member 21 may be shifted, the operating element may effect the engagement of the contact members 9 and 10 before the counteracting element 8 becomes sufficiently energized to effect a balance of the relay 5.

Upon engagement of the contact members 9 and 10, the trip coil 25 of the interrupter 3 is energized from the source of energy 23 and the interrupter is opened to disconnect the circuit from the supply source 1.

The relay 5 may be provided with suitable damping means to preclude instantaneous operation, if desired, and to add a minimum definite time element in its operation, in order to preclude operation of the relay upon occurrence of ordinary switching surges.

The Kelvin balance may similarly be provided with a time element in its operation in controlling the energization of the counteracting element 8 of the balance relay by providing a gear, or other equivalent reducing element, between the motor and the threaded member 20, to either increase or decrease the speed thereof to control the rate of change of energization of the counteracting element 8.

My invention is not limited to the specific apparatus that is illustrated, since it may be variously modified without departing from the spirit and scope of my invention, as set forth in the appended claims.

I claim as my invention:

1. The combination with a distribution circuit of a protective device therefor comprising a balance relay provided with differentially operative elements, means for energizing one element of said relay in accordance with the circuit current, retarded means for energizing another element of said relay to counteract the effectiveness of the first element contacts controlled by said elements and switching means in said circuit controlled by the closure of said contacts.

2. A protective control system for an electric circuit comprising a balance relay embodying two elements, means for energizing one element from the circuit, means for energizing the other element from a separate source and a balance device for controlling the energization of the second element to balance the effect of the first element.

3. The combination with an electric circuit deriving its energy from a power system, of means for isolating the circuit when surge-producing conditions occur in the cir-

cuit comprising an element responsive to the circuit current, a counteracting element and means for controlling the effectiveness of the counteracting element in accordance with the circuit current.

4. The combination with an alternating-current circuit and an interrupter therein, of means energized from the circuit for controlling the actuation of the interrupter upon the occurrence of a surge of current in the circuit said means being ineffective against overload current of the same magnitude.

5. The combination with an alternating-current circuit and an interrupter therein, of means energized from the circuit for controlling the actuation of the interrupter upon the occurrence of a surge in the circuit comprising a balance relay embodying an element energized from the circuit.

6. In an electric circuit, the combination with a circuit interrupter, of means for controlling the actuation of the interrupter when a surge occurs in the system comprising an element energized from the circuit, a counteracting element and means for controlling the effectiveness of the counteracting element in accordance with the circuit current.

7. In an electric circuit, the combination with a circuit interrupter, of means for controlling the actuation of the interrupter when a surge occurs in the system comprising a balance relay embodying an element energized from the circuit and a counteracting element, and a Kelvin balance responsive to circuit currents for controlling the counteracting element.

8. In an electric circuit, the combination with a circuit interrupter, of means for controlling the actuation of the interrupter when a surge occurs in the system comprising a balance relay embodying an element energized from the circuit and a counteracting element, including an operating coil, and a Kelvin balance energized from the circuit for controlling the energization of said coil.

9. In an electric circuit, the combination with a circuit interrupter, of means for controlling the actuation of the interrupter when a surge occurs in the system comprising a balance relay embodying an element energized from the circuit and a counteracting element, including an operating coil, a variable resistor in circuit therewith and a balance device energized from the circuit for controlling the resistor.

10. In an electric circuit, the combination with a circuit interrupter, of means for controlling the actuation of the interrupter when a surge occurs in the system comprising a balance relay embodying an element energized from the circuit and a counteracting element, and means for varying the

effectiveness of the counteracting element within a predetermined rate of change of effectiveness.

11. In an electric circuit, the combination with a circuit interrupter, of means for controlling the actuation of the interrupter when a surge occurs in the system comprising a balance relay embodying an element energized from the circuit and a counteracting element, means independent of the circuit for energizing the counteracting element and means responsive to the circuit current for controlling said means.

12. In an electric circuit, the combination with a circuit interrupter, of means for controlling the actuation of the interrupter when a surge occurs in the system comprising a balance relay embodying an element energized from the circuit and counteracting element, and means responsive to the circuit current for controlling the counteracting element independently of the rate of change of circuit current.

13. In an electric circuit, the combination with a circuit interrupter, of means for controlling the actuation of the interrupter when a surge occurs in the system comprising a balance relay embodying an element energized from the circuit and a counteracting element, means for controlling the energization of the counteracting element within a predetermined rate of change, and means controlled by the balance relay for actuating the interrupter when the rate of change of circuit current exceeds the rate of change of energization controlled by said controlling means.

14. In an electric circuit, the combination with a circuit interrupter, of means for controlling the actuation of the interrupter when a surge occurs in the system comprising

ing a balance relay embodying an element energized from the circuit and a counteracting element, means for controlling the energization of the counteracting element within a predetermined rate of change, and means responsive to the differential torque of the relay elements for controlling the interrupter.

15. The combination with an electric circuit and an interrupter therein, of means for controlling the actuation of the interrupter comprising two counteracting elements, means for energizing one in accordance with the circuit current, means for controlling the energization of the other element within a predetermined rate of change of energization in response to current changes in the circuit, and a control element responsive to the differential action of the counteracting elements.

16. In an electric circuit, the combination with a circuit interrupter, of means for controlling the actuation of the interrupter when a surge occurs in the system, comprising a balance relay embodying an element energized from the circuit, a counteracting element, and retarded means for controlling the effectiveness of the counteracting element.

17. In combination, a distribution circuit, a circuit-interrupter therein, a relay for controlling said circuit-interrupter and means for actuating the contacts of said relay upon the surge of current in said circuit, said means being ineffective upon a gradual increase of current to the same value.

In testimony whereof, I have hereunto subscribed my name this 14th day of May 1923.

HARRY P. SPARKES.
